(57) **CLAIM**

The ornamental design for a knitted glove with conductive elements, as shown and described.

DESCRIPTION

FIG. 1 is a front perspective view of a knitted glove with conductive elements according to my design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The features shown in broken lines are environmental only and form no part of the claimed design.

Dash-dot lines adjacent un-shaded areas represent bounds of the claimed design and themselves form no part of the claimed design.

The shading of the knitted glove with conductive elements in the figures is presented as a patterned texture, which is used to denote that the knitted glove with conductive elements is of a knitted material. The stipple-fill within some of the knitted patterned texture elements within some of the fingertip regions of the knitted glove with conductive elements denotes that the represented portions of the knitted material are of a different or contrasting appearance to the portions of the knitted material represented by unfilled elements. Such stipple-filled elements are dispersed within the unfilled elements in a manner so as to give a marled appearance to the areas of the certain fingertips in which they are present.

A left-handed version of the knitted glove with conductive elements is shown in the Figures. Another embodiment is a right-hand version of the knitted glove with conductive elements that is a mirror image of the embodiment depicted in the Figures, with the exception of the irregular appearance of the colors of the toned areas in the marled yarn, given that the irregularity is an inherent aspect of the yarn's appearance.

1 Claim, 5 Drawing Sheets
